UNITED STATES PATENT OFFICE.

HERMAN A. DAVENPORT, OF BROCKTON, MASSACHUSETTS, ASSIGNOR TO UNITED SHOE MACHINERY COMPANY, OF PATERSON, NEW JERSEY, A CORPORATION OF NEW JERSEY.

HEEL-SUPPORT FOR LASTS.

1,238,894.

Specification of Letters Patent.

Patented Sept. 4, 1917.

Application filed January 12, 1916. Serial No. 71,655.

To all whom it may concern:

Be it known that I, HERMAN A. DAVENPORT, a citizen of the United States, residing at Brockton, in the county of Plymouth and State of Massachusetts, have invented, certain new and useful Improvements in Heel-Supports for Lasts; and I do hereby declare the following to be a full, clear, and exact description of the invention such as will enable others skilled in the art to which it appertains to make and use the same.

This invention relates to heel supports for lasts and more particularly to protectors on heel supports to prevent the shoe uppers from being pinched between the last and the support.

When placing a lasted shoe on the jack of a sole-laying machine, heelng, heel-breasting or other shoe machine, a spindle on the heel support is forced into an iron socket in the heel end of the last. The last is supported while being operated upon by the base of the heel support which surrounds the spindle. The last for the ordinary type of high shoe or boot does not extend to the top of the upper and the portion of the upper extending above the top of the last has a tendency to close in toward the center of the last when it is stretched over the last. The shoe upper, and especially the upper lining, often projects over the last close to the socket in a position to be pinched between the base of the heel support and the top of the last, and when pressure is applied to the last, the upper and lining are damaged.

The primary object of the present invention is to provide a protector for the heel support of a jack which will be positively actuated to move a shoe upper out of the path of the support when the lasted shoe is being jacked.

In accordance with this object one feature of the invention contemplates the provision in a heel support for a last, of an upper spreading member on the support and means for positively actuating the spreading member to move the upper away from the center of the last when the last is being placed on the support.

In the preferred form of the invention the spreading member consists of a pair of arms pivoted on the support having shoe upper engaging teeth which normally are held close to the spindle. A spreader for the arms is mounted in the support and has a cam face in engagement with each of the arms so

that, when the last is placed upon the heel support it engages a stem on the spreader to move the arms apart. The construction of the cam surfaces on the spreader and the surfaces of the spreading arms in contact with the cam of the spreader may be so designed as to give any desired movement to the spreading arms in order to insure that the upper will be moved off from the top of the last when the last is forced upon the spindle.

Still further features of the invention consist in certain novel features of construction, combinations and arrangements of parts hereinafter described and claimed, the advantages of which will be obvious to those skilled in the art from the following description.

The several features of the invention are illustrated in the accompanying drawings in which, Figure 1 is a view in side elevation of the upper portion of a well-known type of sole-laying machine embodying the preferred form of the invention; Fig. 2 is a side elevation of the improved heel support; and Fig. 3 is a rear elevation of the support showing the different positions of the spreading member.

The heel support upon which the improved protecting device is placed consists of a last block 10 and a spindle 12 adjustably mounted in a socket in the block by means of a set screw 14. The block is provided with an opening 16 and set screw 18 by which it may be attached to the heel post of a jack.

To prevent the shoe upper from being pinched between the base of the last block which surrounds the spindle and the top of the last, the heel support is provided with a lining protector which consists of a pair of arms pivotally mounted on the last block and arranged to be spread outwardly from the spindle while the last is being forced upon the spindle. The spreading arms 20 of the protector are mounted on a pivot pin 22 in the edge of the last block 10. The axis of the pivot pin is longitudinal of a supported last, so that the spreading movement of the arms is in a direction transverse to a supported last. The spreading arms 20 are normally held in a position against the spindle 12 by means of a spring 24 which is coiled about the pin 22 and is in engagement with the top of each arm 20. To spread the arms when the lasted shoe is placed upon the

spindle, a spreader 28 is slidably mounted in a boss 26 upon the support 10 below the pivot pin 22 and has two cam surfaces 30, one surface being in contact with a cam face 32 on each spreading arm. The spreader is provided with a stem which projects below the ends of the arms 20 in a position to engage the upper face of the last before the base of the last block 10 comes into engagement with the last. The movement of the last while it is being forced upon the spindle will force the spreader against the cam faces 32 on the spreading arms and move the spreading arms away from the spindle. While the spreading arms are being moved away from the spindle, if the shoe upper is in close proximity to the spindle, a pair of teeth 34 on each of the spreading arms will positively engage the upper and carry it away from the top of the last so that, when the last comes into engagement with the base of the last block, the upper will be away from the top of the last.

The invention is illustrated as embodied in a sole-laying machine, and only the jack of the sole-laying machine is shown in the drawings. This jack consists of a heel post 36 and a toe post 38 mounted upon a cross-head 40. The cross-head is adjustably mounted upon a pair of supporting rods 42, only one being shown. The toe post carries a toe pad 44 and is adjustable along the cross-head 40 relatively to the heel post. The improved heel support is mounted upon the heel post 36 and the spindle 12 is normally forced toward the toe pad by means of a spring 46.

In Fig. 3 the different positions of the spreading members on the heel support are shown. The parts shown in dot and dash lines illustrate one position which the upper may occupy upon the last before the spreading members have drawn it off from the last. In the dot and dash position the upper is drawn across the top of the last in a position such that it would be pinched by the heel support if a protector were not provided. When the last is forced from the position shown in dot and dash lines to the position shown in dotted lines, the spreader 26 is moved by the last to force the spreading arms from the full line position to the position shown in dotted lines. The spreading arms in going from the full line position to the dotted line position positively grip the upper by the teeth 34 and carry it to the position shown in dotted lines. The design of the cams 30 upon the spreader and the cam faces 32 upon the spreading arms is such that the arms are moved outwardly from the spindle and the teeth 34 will move in close proximity to the top of the last and insure that the upper is carried off from the top of the last. Experiments have shown that teeth such as 34 having sharp edges are

necessary to positively grip the upper in starting it away from the top of the last, and by having the curved portion 48 on the spreading arms engage the upper after it has been drawn from the top of the last, a movement of the arms 20 relatively to the upper can be made without injuring the upper or lining.

It is obvious that the design of the cams 30 and 32 can be made to give any desired movement to the spreading arms when acting upon different classes of material to insure that the material will not be pinched between the bottom of the support and the top of the last.

Although the heel support has been illustrated as embodied upon a jack of a sole-laying machine, it is not limited to use in this machine but may be applied to any type of device which employs a heel support for a last.

Having thus described my invention, what is claimed as new, is:—

1. A heel support for a last having, in combination, a last block, a spindle on the block, a spreading member pivotally mounted on the block and supported close to the spindle in a position to move outwardly across a last to spread the upper of a shoe upon the last, and means constructed and arranged to engage the last and move relatively to the spreading member for positively forcing the spreading member away from the spindle when the last is placed on the spindle.

2. A heel support for a last having, in combination, a last block, a spindle on the block, a spreading member mounted on the block and supported close to the spindle in a position to move outwardly across a last to spread the upper of a shoe upon the last, means for positively moving the spreading member away from the spindle in close proximity to the top of the last, and teeth on the spreading member to engage the upper.

3. A heel support for a last having, in combination, a last block, a spindle fixed in the block, a spreading arm pivotally mounted at each side of the block, and a spreader actuating device for moving the arms apart.

4. A heel support for a last having, in combination, a last block, a spindle fixed in the block, a spreading arm pivotally mounted at each side of the block, means for normally holding the arms close to the spindle, and a spreader for moving the arms apart.

5. A heel support for a last having, in combination, a last block, a spindle fixed in the block, a spreading arm pivotally mounted at each side of the block, and a spreader movably mounted in the block to engage the arms and move them apart.

6. A heel support for a last having, in combination, a last block, a spindle on the

block, a spreading arm pivotally mounted at each side of the block, a spreader mounted in the block and having a cam face in engagement with each arm, and a stem on the spreader for engagement with the last whereby the movement of the last in being forced upon the spindle will spread the arms apart.

7. A heel support for a last having, in combination, a last block, a spindle on the block, a spreading arm pivotally mounted at each side of the block, a spring for normally holding the arms in close proximity to the spindle, a spreader having a cam face engaging each arm for moving the arms apart, teeth on the spreading arms for en-

gaging the upper, and a stem on the spreader for engagement with the last whereby the movement of the last in being forced upon the spindle will spread the arms apart. 20

8. A heel support for lasts having, in combination, a last block, a spindle fixed in the block, a spreading arm pivotally mounted at each side of the block, means for normally holding the arms close to the spindle, 25 and a spreader slidably mounted in the block and projecting in advance of said arms for forcing the arms apart and holding them out of contact with the last when the last is placed on the spindle.

HERMAN A. DAVENPORT.
